central propeller stops, the force of the operating side propeller, but it will not act as efficiently for this purpose as it would if it had a counterbalancing side propeller to aid it. It will therefore be seen that an aeroplane having a central propeller and a plurality of propellers at each side of the central propeller, will make the aeroplane safer to use and the stoppage of one propeller. What I claim is:—

A flying machine comprising a plurality of continuous superposed planes forming a cell structure, two fuselages arranged under the middle plane at equal distance from the longitudinal axis of the flying machine and

projecting forward outside said cell structure, a car located transversally at the middle of the cell structure and projecting forward and backward outside said cell-structure, on said cell structure and projecting outside said cell structure and located on an imaginary plane containing the imaginary axis of said fuselages, a motor arranged at the rear end of said car, two motors respectively arranged at the front end of said fuselages, two motors respectively arranged at the projecting ends of said structure supports and propellers respectively connected to the shafts of said motors. In testimony whereof I have signed my name to this specification.

GIANNI CAPRONI.
